UNITED STATES PATENT OFFICE

EDWARD J. KNAPP, OF LA GRANGE, ILLINOIS

COMBINED MAIL BOX, HOUSE NUMBER, KNOCKER, AND LIGHT THEREFOR

Application filed October 28, 1926. Serial No. 144,807.

This invention relates to mail-boxes in general and more particularly to a combined mail-box, house or apartment number, knocker and light therefor, and it is an object of this invention to provide a mail-box having on the exterior thereof a number and an illuminating means therefor which lights up the number, the entrance to the mail-box, and the knocker.

10 The postman or anyone desiring to deliver mail or circulars and the like to a certain address wants first of all to locate the number of the house or apartment and at the same time he wants to find the mail-box so that he 15 may deposit said mail or circulars and the like therein. He frequently must locate both the house or apartment number and the mail-box in a hall-way which is normally dark, and upon locating said number and mail-box he 20 must signal the occupants of the domicile.

It is accordingly an important object of this invention to provide a construction whereby both the house or apartment number and the entrance to the mail-box are lighted up by a 25 convenient light.

It is also an important object of this invention to provide a construction of the above type having means convenient thereto for signaling the occupants of the domicile.

30 Other and further important objects of this invention will be apparent from the disclosures in the specification and accompanying drawings.

The invention in a preferred form is illustrated in the drawings and hereinafter more fully described.

On the drawings:

Figure 1 represents a front elevational view of a door having a device therein embodying 40 this invention.

Figure 2 is an enlarged detail view with parts omitted of Figure 1.

Figure 3 is a fragmentary enlarged detail view taken at the line III—III of Figure 1 45 showing the mail-box door in open position.

Figure 4 is a plan fragment of the back plate containing the slot through which mail is inserted.

As shown on the drawings:

50 In the illustrated embodiment of this invention

tion there is shown a door 1 of a building which has secured on the exterior thereof a plate 2. The plate 2 is provided with an elongated aperture 3 having a central enlarged part 3' which is aligned with a diagonal downwardly sloping aperture 4 extending through said door. The plate 2 is apertured to receive a horizontal conduit 5 which extends through the door 1. A socket 6 is secured to the outer end of the conduit 5 and is provided on its inner end with a mounting 7 for holding an outwardly extending downwardly deflecting reflector 8. A lamp bulb 9 is fitted within the socket 6 and is within the reflector 8. A rectangular door 10 is adapted to close the aperture 3 and is hinged to the plate 2 at the upper edge of said aperture. A suitable house number 11 is provided on the door 10 on the outside thereof and is adapted to be illuminated by the bulb 9 and reflector 8 therefor. A suitable box 12 may be secured to the inner side of the wall 1 beneath the inner end of the aperture 4 to receive therein the mail or the like which slides in through said aperture.

75 A knocker 13 is mounted on the plate 2 and hinged thereto on either side of the aperture 3. A raised lug 14 is provided on the plate 2 beneath the aperture 3 for engagement by the knocker 13.

80 The slot 3 has an enlarged part 3' so that papers or the like may be rolled and passed through the larger part of the slot and yet the slot is not large enough to permit a person to insert his hand and should he do so he cannot reach the mail matter in box 12.

85 In the foregoing construction there is provided a neat and efficient mail-box and knocker which may be readily located simultaneously with the finding of the house or apartment number by the postman. It will be apparent that the foregoing device may be used in the wall of the building instead of the door without departing from the spirit of this invention.

90 I am aware that many changes may be made and numerous details of construction may be varied through a wide range without departing from the principles of this invention, and I therefore do not purpose limiting the pat- 95

ent granted hereon otherwise than necessitated by the prior art.

I claim as my invention:

In a device of the class described, a plate
5 adapted for securement to a wall having an
opening therethrough, said plate having a
slot therethrough for registering with the
opening in the wall, a door hinged to said
10 plate to close the said slot, indicia on said
door, a knocker hinged to said plate, an integral
boss on said plate to receive the impact
of said knocker, and means on said plate for
illuminating said knocker and said door and
15 for illuminating said slot when the door is
raised to the open position.

In testimony whereof I have hereunto subscribed my name.

EDWARD J. KNAPP.
